CLOCK OR SIMILAR ARTICLE

Richard E. Fritz, Winsted, Conn., assignor to The William L. Gilbert Clock Corporation, Winsted, Conn., a corporation of Connecticut

Application September 7, 1954, Serial No. 32,169

Term of patent 14 years

(Cl. D42—7)

FIG.1

FIG. 2

To all whom it may concern:

Be it known that I, Richard E. Fritz, a citizen of the United States, residing at Winsted, in the county of Litchfield, State of Connecticut, have invented a new, original, and ornamental Design for a Clock or Similar Article, of which the following is a specification, reference being had to the accompanying drawing forming a part hereof.

In the drawing:

Fig. 1 is a perspective view of a clock showing my new design, the design being characterized by the element shown in full lines.

Fig. 2 is a fragmentary transverse cross sectional view of the element shown in full lines in Fig. 1.

I claim:

The ornamental design for a clock or similar article, as shown and described.
